David L. Oppenhuizen(57) **CLAIM**

The ornamental design for a display screen with animated graphical user interface, as shown and described.

DESCRIPTION

FIG. 1 is a first image of a display screen with animated graphical user interface;

FIG. 2 is a second image thereof;

FIG. 3 is a third image thereof; and,

FIG. 4 is a fourth image thereof.

The broken lines illustrate a mobile electronic device as well as portions of a graphical user interface. The broken lines form no part of the claimed design. The appearance of the transitional image sequentially transitions between the images shown in FIGS. 1-4. The period in which one image transitions to another forms no part of the claimed design.
